UNITED STATES PATENT OFFICE.

GEORGE LUPTAK, OF RUEGG, MISSOURI.

BOTTLE-CLEANER.

1,303,085.

Specification of Letters Patent.

Patented May 6, 1919.

Application filed September 14, 1918. Serial No. 254,131.

To all whom it may concern:

Be it known that I, GEORGE LUPTAK, a citizen of the United States, residing at Ruegg, in the county of St. Louis and State of Missouri, have invented new and useful Improvements in Bottle-Cleaners, of which the following is a specification.

This invention is an improved manually operable device for cleaning bottles and the like, the object of the invention being to provide an improved device of this character which is simple in construction, which is adjustable for use in bottles of various lengths, and which may be readily attached to and removed from a bottle and may be readily operated.

With the above and other objects in view, the invention consists in the construction, combination and arrangement of devices hereinafter described and claimed.

In the accompanying drawings:

Figure 1 is an elevation, partly in section, of a bottle cleaner constructed and arranged in accordance with my invention.

Figs. 2 and 3 are detail views.

Fig. 4 is a detail elevation of the shaft and one of the cleaner blades.

Fig. 5 is a similar view of the handle grip.

The stock 1 comprises a tube 2 having oppositely extending arms 3, 4. A handle knob 5 is attached to the arm 4 and a beveled gear wheel 5' is mounted for rotation on the arm and is held in place by a screw 6. Said gear wheel is provided with a crank 7 which has a knob 8.

A shaft 9 is swivelly mounted in the tubular stock 2 and is provided with a beveled pinion 10 which engages the beveled gear 5'. The shaft passes through and is mounted for rotation in a cap 11 which may be made of any suitable resilient material, such as brass and which is cylindrical in form, closed at the upper end, and is provided with a longitudinal slot or split 12 which extends therethrough, on one side, from end to end. and also extends radially to the bearing opening through which the shaft 9 passes. Near its lower end the cap is provided with a swelled annular portion 13 which has an annular groove 14. An open clamping band 15 passes around the said groove and the ends of the said band are connected by a screw 16 which has a winged nut 17. The cap can be readily fitted around and over the mouth and neck of a bottle and can be

clamped thereon by means of the band and screw, as will be understood.

At the inner end of the shaft, on opposite sides thereof, are scraper or cleaner blades 18 which are preferably thin steel strips, curved as shown, and which by their own resilience spring apart and are adapted to bear closely against the inner side of the bottle so that when the shaft is turned by means of the gears 5', 10 the cleaner blades are rapidly revolved in the bottle and scrape and thoroughly clean the inner surface thereof. To hold the shaft at any desired adjustment in the cap, according to the depth or length of the bottle, I provide a collar 18a which is secured to the shaft by means of a set screw 19 and which bears on the top of the cap.

At the upper end of the tubular stock is a plug 20 which has a threaded inner portion 21 and an enlarged head 22, said head being provided with oppositely extending studs 23. A handle grip 24 is provided with a sleeve 25 to fit over said head, said sleeve having bayonet slots 26 for the reception and engagement of the studs, to enable the said handle to be detachably secured to the upper end of the stock, when it is desired to use such handle. A sleeve nut 27 is arranged for turning and sliding movement on the upper end of the tubular stock and is adapted to engage the threaded portion of the plug, and to bear against the inner end of the sleeve of said handle, to lock the same when attached to the stock.

The handle knob 5 is grasped by one hand while the crank 7 is being turned by the other hand, to operate the gear. The handle grip 24 is used when applying the machine to the bottle or removing the same therefrom.

While I have herein shown and described a preferred embodiment of my invention, I would have it understood that changes may be made in the form, proportion and construction of the several parts without departing from the spirit of my invention and within the scope of the appended claims.

Having thus described my invention, I claim:

1. A device of the character described comprising a rotary shaft, a hollow cylindrical shell having one end open and its other end closed and provided with a hole slidably engaging upon said shaft, said shell being longitudinally split whereby it may have ex-

panding and contracting movement, said shell being formed to provide an annular groove, and a clamping ring disposed within said groove and adjustable whereby to contract said shell upon the neck of a bottle.

2. A device of the character described comprising a shaft, means for rotating said shaft, cleaner blades carried by the lower end of said shaft, a collar adjacent the lower end of said shaft, a hollow cylindrical shell having one end open and its other end closed

and slidably engageable upon said shaft, means for holding said shell upon said shaft at selected positions thereon, said shell being provided with a longitudinal slit extending into said opening, and a clamping ring engaged externally upon said shell and adjustable whereby to contract said shell into closed engagement with the neck of a bottle engaged therein.

In testimony whereof I affix my signature.

GEORGE LUPTAK.
